(57) CLAIM

The ornamental design for a chocolate rabbit with bow, bell and patch, as shown and described.

DESCRIPTION

FIG. 1 is a perspective view of a chocolate rabbit with bow, bell and patch showing the new design;

FIG. 2 is a front view of the chocolate rabbit with bow, bell and patch design;

FIG. 3 is a left side view of the chocolate rabbit with bow, bell and patch design;

FIG. 4 is back view of the chocolate rabbit with bow, bell and patch design;

FIG. 5 is a left side view of the chocolate rabbit with bow, bell and patch design; and,

FIG. 6 is a top view of the chocolate rabbit with bow, bell and patch design, the bottom not being a part of the claimed design.

The broken lines in the drawings illustrate environmental structure and form no part of the claimed design. The stippling represents a contrasting appearance.
